UNITED STATES PATENT OFFICE

170,065

HOUSING FOR SCIENTIFIC INSTRUMENTS

Thorleif H. Petterson, Pasadena, Calif., assignor
to Beckman Instruments, Inc., South Pasadena,
Calif., a corporation of California

Application December 6, 1952, Serial No. 22,585

Term of patent 14 years

(Cl. D83—1)

To all whom it may concern:

Be it known that I, Thorleif H. Petterson, a subject of Norway, residing at Pasadena, in the county of Los Angeles and State of California, have invented a new, original, and ornamental Design for a Housing for Scientific Instruments, of which the following is a specification, reference being had to the accompanying drawing, forming part thereof, in which:

Fig. 1 is a perspective view of a housing for scientific instruments embodying my new design;

Fig. 2 is a vertical sectional view taken along the line 2—2 of Fig. 1;

Fig. 3 is a top view thereof;

Fig. 4 is a front elevational view thereof;
and

Fig. 5 is a rear elevational view thereof.

I claim:

The ornamental design for a housing for scientific instruments, substantially as shown.

THORLEIF H. PETTERSON.
